UNITED STATES PATENT OFFICE

HENRY ZIEMMERMAN, OF CHICAGO, ILLINOIS, ASSIGNOR TO CHICAGO CARD BOARD COMPANY, OF CHICAGO, ILLINOIS, A CORPORATION OF ILLINOIS

ONE-PIECE FOLDING DISPLAY STAND

Application filed February 21, 1927. Serial No. 169,869.

This invention relates to a card board display stand for illustrating, advertising, or art display, which comprises a single display card of large dimensions adapted to be 5 folded back and forth upon itself in zig-zag fashion, to occupy a minimum space when folded, and to be unfolded or extended into a large single plane.

The object of the invention is to provide 10 a single piece folding easel stand for supporting a card of large dimensions and secured to the card in such a manner that the easel stand is also foldable with the card itself; another object of the invention is to 15 provide lateral stiffeners at the edges of the card which may be folded transversely to the face thereof to stiffen the edges of the display card, and to assist in holding it uniformly in a single plane. Other objects of 20 the invention will appear hereinafter.

Figure 1 is a rear prospective of a display card and its supporting easel constructed in accordance with the principles of this invention;

25 Figure 2 is an edge view of the structure of Figure 1 in partially folded position;

Figure 3 is an end view of the structure of Figure 1 in completely collapsed or folded position; and

30 Figures 4 and 5 are side and rear views of a modification.

In folding display cards for advertising and other purposes, it has long been the desire to provide a folding construction, 35 which, although of large dimensions when in its extended condition, may nevertheless be folded upon itself a number of times so that when it is collapsed it will occupy a minimum space for packing, shipping, and

40 storage. This is accomplished in the present invention by making the display card with alternate fold lines so that it will fold upon itself in zigzag fashion without breaking the outer or display face of the card to an extent 45 which is objectionably visible when the display card is in its distended position. This is accomplished by scoring the card alternately on the opposite sides, the scores in the face of the card being closed when the card 50 is extended.

Likewise, a large display card has heretofore been objectionable because the supporting or easel stand was made separate from or was variably attached to the display card proper. This resulted in much breakage and 55 loss of the parts, the easel stand did not always fit and could not always be set up by the person to whom it was sent. The present construction overcomes all of these objections by rigidly attaching the easel stand to the 60 display card, but by attaching it only to the two outermost folding sections of the card, or to the base section and each alternate section, the intermediate sections being loose 65 or unconnected with respect to the easel stand. The easel stand is provided with fold lines which do not coincide with the fold lines of the card itself so that when the easel 70 is bent into its upholding position and locked in place, there is no tendency for the easel and the display card to break at the same lines. When the card and the easel are folded, however, the fold lines are so disposed that the corresponding sections of the display 75 card and the easel stand are offset laterally with respect to each other, as shown more clearly in Figures 2 and 3. This permits the entire display stand to be folded compactly without danger of breaking either the display card or easel stand at the fold lines, 80 even though they are folded and unfolded many times. By having the easel stand folds offset from the display card folds, there will be a slight bend or give to the protruding ends 85 of these parts which will not put them under severe disruptive strains, as will be evident from Figure 3.

Referring now more particularly to the drawings, a display card is shown having several sections, 1, 2, 3, 4 and 5 connected by opposite fold lines, 6, 7, 8 and 9, the alternate fold lines being on the opposite sides of the display sheet so that the sections will naturally fold upon themselves in zig-zag fashion. It is obvious that a display card may be divided into any desired number of sections which will collapse or fold upon themselves in the same manner. These opposite fold lines are preferably formed by scoring the display card in opposite faces, 90 95 100

but not cutting entirely through the material, so that when in extended position, the fold lines in the face will be substantially closed and the fold lines in the back will not be apparent from the front. Thus it is possible to apply a printed sheet to the face of the card and cut and fold the sheet in the same manner that the card itself is folded; or printing or other decoration may be made directly on the 10 face of the card itself.

At the sides of the display card are stiffeners 10 formed by vertical fold cuts 11 in the face of the display card so that after the card is in distended position, these stiffeners 10 15 may be folded rearwardly and held in place by the natural characteristics of the material itself or may be held in place by mechanical means such as a paster or sticker 12. The score lines in the face and back of the display card extend across these stiffeners 10 just as in the main portion of the board, but they have no material effect when the stiffeners are turned rearwardly, as shown in Figure 1.

25 A folding easel stand 14 is composed of separate sections 14, 15, 16, 17 and 18, corresponding to the scored sections of the display sheet itself and between these sections of the easel stand are score lines 19, 20, 21 30 and 22, the opposite faces corresponding to the score lines of the display sheet. The score lines in the easel stand are offset relatively but parallel to the corresponding score lines of the display sheet and only the outermost 35 sections 14 and 18 of the easel stand are necessarily secured thereto, the intermediate sections being entirely free and unconnected with the corresponding sections of the display card.

40 Preferably, however, each alternate section of the easel is connected to the corresponding alternate section of the display sheet, as clearly indicated in Figure 2, the easel section 16 being secured to the back of 45 display sheet section 3. With this construction it is unnecessary to provide the lateral stiffeners 10 more clearly shown in Figure 1.

At some point intermediate the ends of the easel stand is a locking wing 23 and a corresponding locking notch 24 for holding the folding part of the easel stand locked in distended position. By bending the folding part of the easel stand at right angles to the attached parts, this folding part is readily 55 maintained in a single plane by means of the locking wing, and there is no tendency of the folding part to break or buckle, even though the intermediate sections 15, 16 and 60 17 are not attached to the display card, the easel stand thus constitutes in effect an angular strengthening beam for holding the card in its distended position. Likewise, the 65 strengtheners 10 when bent backwardly have the effect of angular strengthening beams,

thereby holding the outer face of the display card in a single plane.

Referring more particularly to Figures 2 and 3, it will be apparent why the fold lines of the display card and the easel stand do not coincide when these parts are in distended position, and as seen more clearly in Figure 2, the easel stand is offset with respect to the sections of the card so that the folds do not directly coincide even when the entire display stand is in its most compact condition.

When the display card is divided into an even number of sections, as shown by Figures 4 and 5, the easel 25 is attached, as above explained, to each alternate section of the back of the display card, beginning with the bottom section so that the uppermost section 27 of the display card is unconnected and unsupported, and the corresponding uppermost section 28 of the easel bends rearwardly 80 in the same direction when it is folded. When distended, however, the upper section 27 of the card, which bends backwardly in folding, is pressed into the plane of the remainder of the card and held in this position by the uppermost unconnected section 28 of the easel which is held in place by locking wings 29 when they are unfolded and held in place by a lock 30. In this modification, as above explained, the intermediate sections of the easel are not necessarily connected to the display card but they are preferably so connected in order to hold the display card in a distended plane, and if so connected, it is necessary to provide a marginal locking strip, as shown in Figure 1, so that the display card may be cut into various shapes and figures, as shown for example by Figure 5, and still held in a common plane when distended without the necessity of the marginal locking means.

105 I claim:

1. A folding display stand comprising a display card with a plurality of score lines on alternate sides forming sections to fold in zigzag fashion, and an attached folding easel stand with a corresponding number of 110 similarly and concurrently folding sections for supporting the display stand.

2. In a display device of the class described, a display card having folding score lines disposed alternately on opposite sides to fold in a zigzag fashion, and attached means for supporting the card comprising an easel therefore having corresponding score lines disposed alternately on opposite sides 115 and the sections thereof folding concurrently with the sections of the card.

3. In a display of the class described, a card having a plurality of score lines on alternate sides adapting it to fold oppositely upon itself, and an easel stand permanently attached at its ends to the card and having score lines corresponding to those of the card adapting it to fold oppositely with and between the 120 sections of the card.

4. In a display of the class described, a card having scores alternately on opposite sides adapting it to fold upon itself in zig-zag fashion, and a longitudinally folding easel stand secured thereto having scores on alternate sides corresponding to those of the card adapting it to fold in zig-zag fashion concurrently with and between the sections of the card, and means to lock the longitudinally folding portion of the easel stand at right angles to the scores so that the scores in the easel stand will be of no effect when the card is distended.

5. In a display stand of the class described, a display member having a plurality of sections hinged to fold upon each other in zig-zag fashion, and an easel stand comprising foldable sections corresponding to those of the display member also foldable in a zig-zag manner, and alternate sections only of the easel stand and the display member being permanently secured together.

6. A display stand of the class described, comprising a display member having fold lines adapting it to collapse in zig-zag fashion, and an easel with a foldable wing also having transverse fold lines dividing it into sections corresponding to the sections of the display member, the odd sections of the easel being attached to the odd sections of the display member and the intermediate sections of the easel and member having no attachment with each other, the fold lines of the easel being offset with respect to the fold lines of the display member.

7. In a display stand of the class described, a display member having fold lines adapting it to collapse in zig-zag fashion, and a folding easel therefor also having fold lines adapting it to collapse in zig-zag fashion corresponding to the sections of the display member, the alternate sections only of the easel being connected to the alternate sections of the member, and the fold lines of the easel being offset with respect to the fold lines of the member so that the easel and the member will have projecting offset folds at opposite edges of the collapsed structure.

8. In a display stand of the class described, a display member having fold lines adapting it to collapse in zig-zag fashion, and a folding easel therefor also having fold lines adapting it to collapse in zig-zag fashion corresponding to the sections of the display member, the alternate sections only of the easel being connected to the alternate sections of the member, the uppermost sections of the easel and member being unconnected if there are an even number of sections in the member, whereby the uppermost section of the member will be pressed into the plane of the other sections by the corresponding section of the easel when distended.

9. In a display stand of the class described, a display member, and a folding easel there-

for, the stand and easel having opposite fold lines dividing them into an even number of sections to fold in a zig-zag manner, and the corresponding odd numbered sections beginning at the bottom being permanently connected together.

10. In a display stand of the class described, a display member, and a folding easel therefor, the stand and easel having opposite fold lines dividing them into an even number of sections to fold in a zig-zag manner, and the corresponding odd numbered sections beginning at the bottom being connected together, the uppermost free section of the member being folded outwardly by the uppermost section of the easel, the easel having a folding wing which forms an angular supporting section, one web of which fits closely against the rear face of the uppermost display member section when it is unfolded.

11. In a display stand, a display member alternately scored on opposite sides to fold in a zig-zag manner and forming a plurality of sections, an easel with a folding wing and transverse score lines corresponding with those of the member, the odd sections of the easel beginning at the bottom being attached to the corresponding sections of the member with the edges of the sections of the easel and the member overlapping so that their fold lines are relatively offset, the base section of the display member being wider than the other sections to cover and protect the folds of the easel when the display stand is folded.

12. In a display stand, a display member alternately scored on opposite sides to fold in a zig-zag manner and forming a plurality of sections; an easel with a folding wing and transverse score lines corresponding with those of the member, the odd sections of the easel beginning at the bottom being attached to the corresponding sections of the member, the uppermost sections of the easel and member being free when the member has an even number of sections, and the folding wing engaging the uppermost section of the member to press and hold it in the plane of the other sections when it is distended.

13. In a display stand, a display member and an easel stand oppositely scored to fold together in a zig-zag manner, the first and last odd numbered sections, beginning at the base, being connected together, the uppermost section of each being free when the display stand has an even number of sections, and the free easel section operating to press and hold the free section of the member in the plane of the other sections when it is distended.

14. In a folding display stand of the class described, a display card having alternate scores in opposite faces adapting it to fold in a zig-zag manner, and lateral scores in the same face to form stiffening edges when the
